UNITED STATES PATENT OFFICE.

JAMES OGG, OF PAHALA, TERRITORY OF HAWAII.

SUGAR-CANE MILL.

1,124,643.

Specification of Letters Patent.

Patented Jan. 12, 1915.

Application filed May 2, 1914. Serial No. 835,908.

To all whom it may concern:

Be it known that I, JAMES OGG, a subject of the King of Great Britain, residing at Pahala, in the county of Hawaii and Territory of Hawaii, have invented certain new and useful Improvements in Sugar-Cane Mills; and I do hereby declare the following to be a full, clear, and exact description of the invention, such as will enable others skilled in the art to which it appertains to make and use the same.

This invention relates to improvements in sugar-cane mills, and particularly to such mills having three rollers in triangular arrangement. Its object is to increase the work performed by such mills and their efficiency.

Since the recent introduction of deep, narrow grooving for rolls, the feed roller of a three roller sugar-cane mill thus grooved can be set closer to the top roller than heretofore, as the rollers with such grooving take the feed even when they are set closely together. Consequently these rollers now express a large proportion of the juice in the cane or bagasse passed between them. These rollers, therefore, now do the work which has usually been done by the top roller and the discharge roller, thus leaving little work for the latter roller to do.

The present invention contemplates a novel means for applying maceration liquid, through the toe or blade of the returner-bar, to the bagasse discharged from between the top roller and the feed roller of a sugar-cane mill, and particularly of a mill having the roll grooving mentioned. This maceration liquid, either hot water or diluted juice, takes up sucrose from the bagasse, and together with a percentage of the juice in the bagasse is expressed when this macerated bagasse passes between the top roller and the discharge roller, thus giving work for these rollers to perform. As a result, the capacity of the mill is increased, the effect being almost equivalent to the addition of another mill. As the juice from the cane or bagasse expressed by the feed roller is richer in sucrose than that expressed from the bagasse by the discharge roller, these juices may be caught and strained separately, in order that the weaker or diluted juice may be used for maceration in connection with a previous mill in the train.

A fourth roller has heretofore been added 55 on the discharge end of three roller sugar-cane mills, to increase the efficiency of the mill. The present invention, however, contemplates a simple and effective means for applying a fourth roller with hydraulics to 60 an existing three roller sugar-cane mill.

This invention further contemplates, when a fourth roller is employed, a returner-bar above the discharge roller and forward of the fourth roller, with means to cause its toe 65 to bear against the top roller, and also means for applying maceration liquid through the blade or toe of said returner-bar. The bagasse discharged from between the top roller and the discharge roller is 70 thus macerated during its passage under this returner-bar. The maceration liquid, which takes up sucrose in this bagasse, is expressed when this macerated bagasse passes between the fourth roller and the discharge 75 roller. The resulting juice may, when low in sucrose, be applied for macerating the bagasse in other mills in the train.

The invention consists in the novel combination and arrangement of parts as herein- 80 after described and claimed.

The accompanying drawing, forming a part of this specification, illustrates in side elevation a three roller sugar-cane mill embodying my improvements.

Referring to the drawing, 1 represents the housing, 2 the top roller, 3 the feed roller, and 4 the discharge roller, respectively, of a three roller sugar-cane mill.

The blade 5 of its returner-bar is provided with a plurality of holes 6 through the blade rearward of its toe. The lower end of each hole 6 is threaded to receive a pipe 7. Each pipe 7 is connected by a union 8 to a nipple 9 in the header or manifold 10. I 95 make these holes 6 one-quarter of an inch in diameter, spaced about one and one-half inches apart, and the pipes 7 of one-eighth inch pipe, although I do not confine myself to these sizes, which may be altered to suit 100 the conditions. The maceration liquid, supplied under pressure through the manifold 10, passes successively through the nipples 9, the pipes 7, and the holes 6, into the bagasse passing over the blade 5 of the returner-bar. Grooves 11 may be provided in the top of the blade 5, rearward from each hole 6, in order that trash may be swept

2
rearward with the bagasse on the blade 5 and prevent the holes 6 from becoming plugged therewith.

The fourth roller 12 is similar to the lower rollers of the mill. The teats 12^a on the ends of the shaft of the roller 12 are adapted to revolve in the brasses 13. The teats 4^a on the ends of the shaft of the discharge roller 4 are provided with similar brasses 14. The bolts 15, 16 connect the upper bridle plate 17 and the lower bridle plate 18. The hydraulic jack 19 with its plunger 20 is interposed between the brass 14 and the lower bridle plate 18. A dowel or boss 13^a on the brass 13, 19^a on the hydraulic jack 19, and 20^a on the plunger 20, fit corresponding holes in the upper bridle plate 17, in the brass 14, and in the lower bridle plate 18, respectively, to preserve alinement. The pipe 21 connects the hydraulic jack 19 with the pipe 22, which connects the jacks of the three roller mill with their accumulator. The area of the jacks 19 may be only about one-fifth that of the jacks of the three roller mill. A strap 23, of flexible material such as spring steel plate, is provided for each side of the mill to connect the upper end of the bolt 15 with the upper end of the rear king bolt 24 of the mill. The bolts 15 and 24 pass through holes in the strap 23, the straps being clamped between the nuts of said bolts and the bridle plates, as shown. The pinion of the roller 12 meshes with that of the discharge roller 4, so that the roller 12 is thus driven by the discharge roller 4. After the position of the roller 12 has been determined, with a suitable opening between this roller and the discharge roller 4, babbitt is run in between the journals 12^b of the roller 12 and the housings 1, to form bearings 25, as shown. The journals 12^b of the roller 12 thus revolve in the babbitted bearings 25 when the mill is running light or without cane, and the approach of the roller 12 toward the discharge roller 4 is thus limited.

The returner-bar 26 is located above the discharge roller 4 and forward of the fourth roller 12, as shown. By tightening the nut 27 on the bolt 28, which passes through the pin 29 in the housing 1, the lever 30 may be pulled, and thus cause the toe of the returner-bar 26 to press against the top roller 2.

The returner-bar 26 is provided with a plurality of holes 31 through its blade near its toe, as shown. A pipe 32 screwed into each hole 31 is connected by a union 33 with a nipple 34 in the manifold 35. Grooves 36 may be provided in the returner-bar 26. This arrangement is similar to that previously described, but inverted, as shown.

The pipe 37, rearward of the returner-bar 26 and provided with holes and connected to a pump, may be employed to withdraw

the expressed juice which is forced forward when the macerated bagasse passes between the fourth roller 12 and the discharge roller 4.

I claim:

1. In a sugar-cane mill, a returner-bar provided with a plurality of holes through its blade near its toe, a manifold, and pipes connecting said holes with the manifold, substantially as and for the purpose described. 70

2. In a sugar-cane mill, a returner-bar, a plurality of holes through the blade of the returner-bar, a manifold, pipes connecting said holes with said manifold, and grooves 80 in the blade rearward from said holes, substantially as and for the purpose described.

3. In a sugar-cane mill, the combination with three rollers in triangular arrangement, of a fourth roller co-operating with the discharge roller, a returner-bar above the discharge roller and forward of the fourth roller, means for pressing the toe of the returner-bar against the top roller, and means for applying maceration liquid through said 90 returner-bar near its toe, substantially as described.

4. In a sugar-cane mill, the combination with three rollers in triangular arrangement, of a fourth roller, a returner-bar forward of the fourth roller, means for pressing the toe of the returner-bar against the top roller, said returner bar provided with a plurality of holes therein and a plurality of grooves, a manifold, and pipes connecting 10 each of said holes with the manifold. 95

5. In a sugar-cane mill, the combination with three rollers in triangular arrangement, of a fourth roller co-operating with the discharge roller, two bridle plates, bolts connecting the same, brasses in which the teats of the fourth roller and of the discharge roller are journaled, and a hydraulic jack with its plunger interposed between one of the said bridle plates and one of said brasses, 11 substantially as described.

6. In a sugar-cane mill, the combination with three rollers, of a fourth roller, two bridle plates, bolts connecting the same, brasses between said bolts in which the teats of the fourth roller and of the discharge roller are journaled, a hydraulic jack with its plunger between one of the bridle plates and one of the brasses, and a flexible strap connecting one of said bolts with the top of 1 the mill, substantially as described.

7. In a sugar-cane mill, a housing, four rollers, two bridle plates, bolts connecting the same, brasses between said bolts in which the teats of two of the rollers are journaled, a hydraulic jack with plunger between one of the brasses and one of the bridle plates, and a babbitted bearing on the housing adapted to fit the journal of the fourth roller, substantially as described.

8. In a sugar cane mill, a returner bar provided with a plurality of holes therein, and means to supply maceration liquid through said holes.
- 5 9. In a sugar cane mill, the combination with three rollers in triangular arrangement, of a fourth roller coöperating with the discharge roller, a returner bar above the discharge roller and forward of the fourth

roller, and means for supplying maceration liquid through the returner bar, substantially as described.

In testimony whereof I affix my signature, in presence of two witnesses.

JAMES OGG.
